UNITED STATES PATENT OFFICE.

JOSEPH MESSINGER, OF PHILADELPHIA, PENNSYLVANIA.

SPOKE-EXTRACTOR.

966,461.

Specification of Letters Patent.

Patented Aug. 9, 1910.

Application filed May 4, 1909. Serial No. 493,778.

To all whom it may concern:

Be it known that I, JOSEPH MESSINGER, a citizen of the United States, residing in the city and county of Philadelphia, State of Pennsylvania, have invented a new and useful Spoke-Extractor, of which the following is a specification.

My invention consists of a device for extracting spokes from hubs of wheels, etc., embodying clamps for tightly engaging the spokes, and means including a hydraulic jack for imparting motion to said clamps, whereby the spokes follow the same.

It further consists of details of construction, as will be hereinafter described and claimed.

It further consists in adapting the device to be used where the spokes are so constructed that it cannot be seated on the wheel hub.

For the purpose of explaining the invention, the accompanying drawings illustrate a satisfactory reduction of the same to practice, but the important instrumentalities thereof may be varied, and so it is to be understood that the invention is not limited to the specific arrangement and organization shown and described.

Figures 1 and 2 represent side elevations of a spoke-extracting device embodying my invention. Fig. 3 represents a longitudinal section of a portion thereof on line $x-x$, Fig. 2, on an enlarged scale. Fig. 4 represents a section of a portion on line $y-y$, Fig. 1. Fig. 5 represents a transverse section on line $z-z$, Fig. 1. Fig. 6 represents a section on line $a-a$, Fig. 4. Fig. 7 represents a section of a portion of the device. Fig. 8 represents a perspective view thereof on an enlarged scale. Fig. 9 represents a side elevation thereof.

Similar letters of reference indicate corresponding parts in the figures.

Referring to the drawings:—A designates a hydraulic jack whose supply chamber or casing B' is attached to a fluid tight cylinder or chamber B, said casing and chamber having a valved communication, within which chamber is the ram or piston C, the latter having connected with its exterior end as at C', the legs D, whose feet E are adapted to be rested on the hub F, from which spokes are to be extracted. The supply chamber B' is on the outer end of the cylinder B and contains a pressure cylinder, a plunger in the latter and operating means

for said plunger journaled in said chamber. The legs D form rigid thrust-sustaining bars, which extend from the piston C and are adapted to straddle a spoke.

G designates a cross head or yoke, which is connected with rods H, the latter extending in the longitudinal direction of the device the same as the piston bars D and having the ends opposite to said yoke G connected as at J with the wall of the chamber B of the hydraulic jack A. The yoke G is of the order of an open frame, within which are the clamps K, whose outer faces are wedge-shaped and whose inner faces are serrated as at L, said clamps being adapted to occupy positions on opposite sides of a spoke to be extracted and the serrations L to engage said spoke. The opposite sides of the inner face of the yoke G have wedge-shaped walls M, which are adapted to ride on the wedge-shaped faces of the clamps K, when the yoke receives motion, and thus gradually tighten the clamps against the spoke. The opposite sides of the inner face of the yoke have also therein the recesses N to receive freely the legs D. In order to prevent upward-displacement of the clamps from the yoke G, the lower ends of the former have screws P connected therewith, the same projecting outwardly from the clamps, so that when the latter are raised to full extent, they abut against the yoke as stops, the effect of which is evident.

The operation is as follows:—The legs E are placed on a hub, and the clamps occupy positions on opposite sides of the spoke to be extracted from said hub, as most plainly shown in Fig. 2. The hydraulic jack is then operated, whereby the water or fluid enters the chamber B under pressure, as usual in such cases. The ram C remains stationary under said pressure, while the connected legs D are seated on the hub. As the shell or casing of the jack is freely fitted on the ram, it receives motion in the direction of the arrows, and draws with it the rods H and the yoke G, the latter acting as a follower and acting first upon the clamps K to tighten them against the spoke, and next, carrying the clamps with said yoke, and thus the engaged spoke follows the clamps and is thereby extracted from the hub. The hydraulic jack is now operated, whereby the water or fluid leaves the chamber B and enters the other chamber B', thus relieving said chamber B of pressure, when the shell or casing

of the jack may be moved in a direction the reverse of the arrows. This releases the clamps K of the tightening action of the yoke G, when they are comparatively loose and disconnected from the spoke, ready to be applied to another spoke to be extracted, when the legs are properly seated on the hub.

In order to guide the clamps and avoid displacement of the same, the inner sides of the yoke G have inturned tongues Q, which freely enter the grooves or recesses R on the sides of the clamp, as readily understood on reference to Fig. 4.

Where the spokes are provided with shoulders S, which join each other, as well known, see Figs. 7 and 9, the legs D cannot be seated directly on the hub of the spoke. To provide for this, I employ the separate box or saddle T having depending sides U, which are adapted to straddle said shoulders and to be seated on the wheel hub, see Figs. 7 and 9.

In the outer or upper walls of the box are recesses V, in which the feet E of the legs D are seated and so prevented from slipping, and said box is also provided with screws W, which are adapted to bear against the opposite sides of the spoke, simply to steady the box, but the clamps are employed to engage said spoke and receive motion to extract the latter, as in the previous case.

Having thus described my invention, what I claim as new and desire to secure by Letters Patent, is:—

35 1. A spoke extractor comprising a hydraulic jack cylinder, and a piston, the latter having rigid thrust-sustaining bars extending from its outer end and adapted to

straddle a spoke, the cylinder having rods secured thereto and projecting therefrom in the same direction as said piston bars, a cross head carried and guided by said rods and having spoke-engaging devices, a supply chamber secured to the outer end of the cylinder, a pressure cylinder, and a plunger 45 inclosed in said chamber, and operating means for said plunger mounted in said chamber.

2. In a spoke extractor, a hydraulic jack cylinder, a fluid-supply chamber connected with the outer end of said cylinder, a piston within said cylinder, thrust-sustaining bars extending from the outer end of said piston and adapted to straddle a spoke, rods secured to said cylinder and projecting in the same direction as said thrust bars, a cross head carried by said rods, spoke-engaging devices in said cross head, and a pressure cylinder, a plunger, and operating means for said plunger in said chamber, said piston with the attached thrust bars being stationary, and said rod-carrying cylinder being movable outwardly on said piston.

3. In a spoke extracting device, a saddle disconnected from said device adapted to straddle a shouldered spoke and having its sides adapted to be seated on a hub, and means on said saddle adapted to engage the sides of a spoke to steady said saddle thereon, said saddle having means on top for freely seating thereon the thrust-bearing bars of said device.

JOSEPH MESSINGER.
